UNITED STATES PATENT OFFICE.

PERCY J. CALLOWHILL, OF PROVIDENCE, RHODE ISLAND, ASSIGNOR TO THEODORE W. FOSTER & BRO. CO., OF PROVIDENCE, RHODE ISLAND.

LOOSE-POWDER CONTAINER.

Application filed January 27, 1926. Serial No. 84,139.

This invention relates to certain new and useful improvements in loose powder containers, and the primary object thereof is to provide a device of this type wherein 5 the powder may be dispensed or ejected by rotation of the sifter or by tapping same with a finger.

A further object of the invention is to provide a device of this kind which prevents 10 leakage of the powder, and which also can be easily and quickly operated to replenish the powder supply.

Still further, the invention aims to provide a device of this type which affords a 15 combined powder container and rouge holder as a unit, the powder being expelled from one side of the container and the latter being filled from its opposite side, the filling opening being covered by a closure which 20 latter is formed to receive a cake of rouge.

In the drawings:—

Fig. 1 is a plan view of a vanity case in open position and showing the present invention applied thereto;

25 Figure 2 is an elevation of the invention, partly broken away and in section;

Figure 3 is a section on line 3—3 of Fig. 2;

30 Figure 4 is a section on line 4—4 of Fig. 3, and

Figure 5 is a section on line 5—5 of Fig. 3.

In proceeding in accordance with the present invention a case of any type may 35 be used, the one shown, for instance, having a body 1, provided with a cover 2 hinged thereto at 3 and equipped with a mirror 4.

The invention embodies a powder container 40 composed of a ring like body 5 offset at its top to form a circular shoulder 6 and having its upper edge curled inwardly and downwardly as indicated at 7.

The sifter is composed of a mesh or fo- 45 raminated thin metal disk 8 secured to a ring 9, which latter clampingly carries a felt ring or packing 10 that extends outwardly from the periphery of the ring and which seats on a split ring 12 (Fig. 5) that is engaged 50 on the shoulder 6 and which in turn is engaged by the curled edge 7 of the body 5.

The packing 10 is freely rotatable in the channel provided by and between the curled edge 7 and the ring 12 on shoulder 6, for which purpose the ring 9 is provided with 55 a finger engaging piece or projection 11. The felt ring 10 not only provides a rotatable mounting for the screen, but also yieldingly supports the screen at its periphery and further acts to prevent leakage 60 about the screen periphery thereby confining the passage of the powder to the screen at the central part of the screen.

A U- or channel ring 13 abuts the under 65 face of the offset part of body 5 and clampingly carries a felt packing ring 14. The ring 13 may be soldered to the body 5 in encircling rotation thereto, its under face forming a circular stop for the inturned edge 15 of the rim 16 of a cover 17. 70

The cover 17 closes and forms the bottom 75 of the body 5 and is removable from the latter so as to enable a supply of powder to be applied to the container. For the purpose of removably mounting the cover 17 80 on the body 5, the latter is provided with a pair of diametrically opposed pins 18 which latter are receivable in a pair of diametrically opposed slots 19 formed in the rim 6 of the cover. It will thus be seen that 85 by positioning the cover to bring its slots 19 into register with the pins 18, the latter may engage beneath the inturned edge 15 of the cover, as depicted in Fig. 2, and upon turning of the cover same will be held in 90 position on the body 5.

The bottom 17 not only serves as a closure 95 for the body 5 but also functions as a support for the follower and for a cake of rouge. The follower is composed of a metal disk 20 having a felt facing 21 which at its periphery engages the inner circumference of body 5. As illustrated in Fig. 4, the disk 21 has a series of spring feet 23 struck-out therefrom, which feet seat on the 95 cover 17 and thus resiliently support the follower. In order to perform its functions of carrying a cake of rouge, the cover is formed with a circular depressed part 24 forming a cup to receive a cake of rouge R. 100 The cup rim has a series of lugs 25 which serve to retain the cake of rouge therein.

From the foregoing it will be seen that the powder may be expelled by rotation of the sifter 8 or by tapping the latter with a finger. The follower acts to resiliently support the powder and upon movement resultant from agitation of the powder expels the latter through the screen.

The entire device as a unit may be carried in a vanity case and removed therefrom if desired to obtain a supply of powder or to have access to the rouge. The powder may however be expelled while the container remains in the case, if desired.

The container may also be used with different sized vanity cases, as is obvious, and in such instances rings 14 of corresponding different sizes may be used.

To refill the body with powder, the closure 17 is first removed and then the follower and after placement of the powder in the body, the follower is first inserted and the closure then secured in position on the body.

Having thus described my invention what I claim as new and desire to secure by Letters Patent is:—

1. In a powder container, a ring-like body having an interior channel at its upper portion, a screen, a felt ring carried by the ring and being rotatably disposed in the channel a closure for the bottom of the body, a metal disk having a felt facing engaged within the body and below the screen, said disk having spring feet struck-out therefrom and seated on the closure, means to removably secure the closure to the body, a channeled ring secured to and about the periphery of the body, and a felt ring in the channeled ring extending outwardly therefrom.

2. In a powder container, a ring-like body having an interior channel at its upper portion, a screen a ring secured to and about the screen, a felt ring carried by the first ring and rotatably disposed in the channel, a closure for the bottom of the body, a metal disk having a felt facing engaged within the body and below the screen, said disk having spring feet depending therefrom and seated on the closure, and means to removably secure the closure to the body.

3. In a powder container, a body, a spring follower in the body, a screen above the follower and having a felt ring secured to and extending outwardly from its periphery, means to rotatably mount the ring in the body, for movement in a single plane and a closure for the body supporting the follower.

4. An insert for vanity cases, including a powder holding body, a packing ring secured to the periphery of the body and extending outwardly therefrom, and formed to frictionally engage with the inner face of the circumferential wall of a vanity case, a closure for the bottom of the body, means

to removably mount the closure on the body, a resilient follower supported by the closure, and a screen at the top of the body.

5. An insert for vanity cases, including a powder holding body, a packing ring secured to the periphery of the body and extending outwardly therefrom, and formed to frictionally engage with the inner face of the circumferential wall of a vanity case, a closure for the bottom of the body, means to 70 removably mount the closure on the body, a resilient follower supported by the closure, a screen at the top of the body, and means to mount the screen for bodily rotary movements in a single plane and for vertical 75 vibratory movement.

6. An insert for vanity cases, including a powder holding body, a packing ring secured to the periphery of the body and extending outwardly therefrom, and formed to frictionally engage with the inner face of the circumferential wall of a vanity case, a closure for the bottom of the body, means to 80 removably mount the closure on the body, a resilient follower supported by the closure, 85 said body having an interior channel at its top, a screen, and packing carried by the screen and rotatably engaged in the channel to support the screen in a single plane and to allow same to yield relative to the body. 90

7. In a powder container, a body having a circular channel and a powder compartment, a screen, and a felt ring rotatably mounted in the channel and connected to the periphery of the screen to both rotatably 100 and yieldably support the screen.

8. In a powder container, a body, a rotatable screen on one side of the body, a closure for the opposite side of the body, a follower in the body between the screen and closure, means to resiliently support the follower from the closure, and packing carried by the body and extending outwardly from the periphery thereof.

9. In a powder container, a body having a circular channel and a powder compartment, a screen, and means connected to the screen and rotatably mounted in the channel for supporting the screen for rotary movement in a single plane.

10. In combination with a vanity case, a bodily removable powder container therefor, composed of a body having a powder compartment, and packing encircling the body whereby to cause the packing to frictionally engage and be removably held in the case.

11. In combination with a vanity case, a bodily removable powder container therefor, composed of a body having a powder compartment, the body having a peripheral channel and a packing ring secured in the channel and frictionally engaged with the interior of the body so as to removably hold the body within the case.

12. In a vanity device, a body having a powder compartment, a screen extending over one side of the compartment, a removable closure for the other side of the body having an integral rouge cake receiving cup which latter extends interiorly of the compartment, a follower between the screen and

closure, and spring means to support the follower from the closure extending across the periphery of the cup.

10

In testimony whereof I have signed my name to this specification.

PERCY J. CALLOWHILL.
